(57) **CLAIM**

The ornamental design for an electronic cigarette consumable, as shown and described.

DESCRIPTION

FIG. 1 is a front, top, and left side perspective view of an electronic cigarette consumable showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof; and,

FIG. 8 is another front, top, and left side perspective view thereof.

The evenly spaced broken lines shown in the drawings depict portions of the electronic cigarette consumable that form no part of the claimed design.
